DESIGN FOR AN ADVERTISING WALL CLOCK

Murray Smole and Louis Berg, Brooklyn, N. Y.

Application October 24, 1947, Serial No. 142,124

Term of patent 3½ years

(Cl. D42—7)

To all whom it may concern:

Be it known that we, Murray Smole and Louis Berg, citizens of the United States of America, residing in Brooklyn, county of Kings, and State of New York, have invented a new, original, and ornamental Design for an Advertising Wall Clock, of which the following is a specification, reference being had to the accompanying drawing, forming part thereof.

Figure 1 is a front view of an advertising wall clock, showing the essential features of our new design in full lines.

Figure 2 is a side view of the advertising clock shown in Figure 1.

We claim:

The ornamental design for an advertising wall clock, as shown and described.

MURRAY SMOLE.
LOUIS BERG.
